[57] CLAIM

The ornamental design for a vehicle overhead console, substantially as shown and described.

DESCRIPTION

FIG. 1 is a rear elevational view of a vehicle overhead console embodying our new design;

FIG. 2 is a bottom plan view thereof;

FIG. 3 is a side elevational view thereof taken from the left side of FIG. 1;

FIG. 4 is a side elevational view thereof taken from the right side of FIG. 1;

FIG. 5 is a top plan view thereof;

FIG. 6 is a rear elevational view of a vehicle overhead console showing a second embodiment of our new design;

FIG. 7 is a bottom plan view of FIG. 6;

FIG. 8 is a side elevational view of FIG. 6 taken from the left side thereof;

FIG. 9 is a side elevational view of FIG. 6 taken from the right side thereof;

FIG. 10 is a top plan view of FIG. 6;

FIG. 11 is a rear elevational view of a vehicle overhead console showing a third embodiment of our new design;

FIG. 12 is a bottom plan view of FIG. 11;

FIG. 13 is a side elevational view of FIG. 11 taken from the left side thereof;

FIG. 14 is a side elevational view of FIG. 11 taken from the right side thereof; and

FIG. 15 is a top plan view of FIG. 11.
